INVENTOR
DAVID SPITTAL

BY
David Spittal

ATTORNEY

UNITED STATES PATENT OFFICE.

DAVID SPITTA, OF CHAMBLEY BASIN, QUEBEC, CANADA.

GOLF CLUB.

Application filed December 28, 1927, Serial No. 246,075, and in Canada August 11, 1927.

My invention relates particularly to golf clubs of the wooden type although it may be applied to the irons. The invention has for its object to provide a club which will combine the good qualities of both the steel and hickory shafts with attendant elimination of torsion, while maintaining the spring of the wood shaft. A further object of my invention is to reestablish the ancient club-making industry and I do this by producing a golf club having an all-wood hickory shaft sheathed with a steel shaft from the sole of the club-head to a point slightly less than half the length of the club. Both steel and wood shaft portions are rigidly anchored at the sole of the head and are united at the upper end of the steel. In this manner the steel portion of the shaft, which has heretofore been hollow or filled with a material relatively soft as compared with hickory, is completely filled by the tightly fitting hickory shaft within it, thus eliminating the vibration so common to steel shaft clubs, and therefore eliminating cracks and breakage in the head due to the vibration. In order to effect a positive joint between the hickory and steel at the upper end of the steel, I provide a copper sleeve or jacket for the upper end of the steel, thus reinforcing that end of the steel and with a through pin engaging both steel and hickory and, in effect, producing an integral hickory steel shaft.

Another feature of my invention has for its object to provide a perfect joint between the wood and steel shaft portions and render invisible the rivet for uniting them together.

For full comprehension, however, of my invention, reference must be had to the accompanying drawings in which similar reference characters indicate the same parts and wherein:

Figure 1 is a side elevation of a driver constructed according to my invention;

Figure 2 is a side elevation of the jointed portion of the club drawn to a larger scale;

Figure 3 is a sectional view taken on line 3-3 Figure 2;

Figure 4 is a transverse horizontal sectional view taken on line 4-4 Figure 2; and

Figure 5 is a plan view of the sole of the club.

The head *b* of my club may be of any preferred construction, a driver, a brassie, a spoon, or an iron. I provide a full length hickory shaft with the usual hand grip *e*.

Its steel shaft portion *c* is set into the head through the neck *d* of the head and rigidly secured in place as by extending it through the head to the sole where it is rigidly anchored. I prefer to make the steel shaft portion slightly less than one-half of the normal length of the club so that the full spring of the hickory may be maintained. Lower portion 13 is reduced in diameter equal to the interior diameter of and adapted to snugly fit within the usual tubular steel shaft, a portion of which, approximately one-half the length of the hickory shaft is used. This reduced portion of the hickory shaft is continued integrally throughout its length and with the steel shaft end is inserted through the neck *d* of the head to the sole *g* thereof. A wedge *h* locks the ends of the hickory shaft and through it the steel shaft in the head at the sole. In order to prevent torsion and vibration a rivet *i* locks the hickory shaft and steel shaft portion together and to the head of the club at the neck of the head, thus effectively preventing torsion between the head and the hickory shaft and the steel shaft portion. Another copper rivet 16 locks the hickory shaft and steel shaft portion together at the head of the steel shaft portion. The torsion and vibration usually apparent in all steel shafted golf clubs is most undesirable and spoils the work of the player, and also damages the club. To augment this relief I provide a deepened shoulder 10 in the hickory shaft, the shoulder being equal in depth to the thickness of the metal of the steel shaft portion *c* and a short copper sleeve or jacket 15 enclosing and securely fastened to the upper end of the steel shaft portion. This copper sleeve or jacket is tapered downwardly from its outside to its inside as indicated in Figure 3 so as to cause the surfaces of the jacket and steel shaft portions to merge when they are united. The upper ends of the jacket and steel shaft portion are secured to the hickory by the copper rivet 16 which owing to the sleeve being also of copper enables an invisible joint to be effected between the rivet ends of the jacket. This connection forms a joint between the steel and hickory which is sufficiently thick to effect a relatively wide bearing between the hickory shaft and steel shaft portion, thus solidifying and strengthening the entire shaft without detracting from the inherent spring in the hickory shaft.

In my club the hickory 12 is continuous from the handle *e* to the sole *g* of the club and reinforced by the steel portion *c* which is without vibration because of the solidity 5 imparted to it by the perfect fit of the hickory shaft within its entire length, and the rigid connection of both the hickory and steel to the head, the whole being further solidified without detracting from the spring 10 of the hickory, by the copper jacket 15 and copper rivet 16. My improved club has no vibration while maintaining maximum spring. The results obtained by my club are in consequence superior to those obtained 15 with any other club ever used by me. In the ordinary steel shaft clubs the disadvantage of vibrations is caused in the shaft by each stroke due to the impact of the head of the club with the ball and torsion is produced 20 in the same way in all clubs. This vibration, recognized as the hum by golf players is concentrated in and eventually produces cracks in the head of the club and the splitting and destruction of it which is supplemented by the torsional strains. This disadvantage is entirely overcome by tightly 25 fitting the steel part of the shaft over the hickory shaft which extends continuously from the top of the handle to the sole of the 30 head where they are permanently and solidly fastened.

I have found that a golf club constructed according to my invention is free of torsion because of the fact that the hickory shaft is 35 rigidly secured in the head of the club and

fits snugly within the steel shaft portion without play between them while the steel shaft portion is united rigidly to the hickory shaft. The results obtained from this construction of golf club are superior to those 40 obtained from either steel or wood shaft clubs.

What I claim is as follows:

1. A golf club consisting of a head and a combined steel and hickory shaft, the steel 45 shaft extending up the hickory shaft for substantially half of its length, means securing the foot of the steel shaft to the head of the club, the hickory shaft extending through the steel shaft and the head 50 to the sole of the head, means locking the ends of the steel and wood shafts to the head at the sole and reinforcement means uniting the top of the steel shaft portion to the hickory shaft. 55

2. A golf club such as claimed in claim 1, the hickory shaft being reduced in diameter for a portion of its length and presenting a relatively wide shoulder and the steel shaft fitting snugly over the reduced portion of 60 the hickory shaft and abutting against the shoulder, and a jacket enclosing and rigidly united to the top of the steel shaft portion and abutting against the shoulder, and a rivet uniting the jacket and steel shaft to 65 the hickory shaft and grip material wound upon the upper end of the hickory shaft.

In testimony whereof I have signed my name to this specification.

DAVID SPITTAL.
